UNITED STATES PATENT OFFICE

MICHAEL J. McHALE, OF SCRANTON, PENNSYLVANIA

FLYER CONSTRUCTION

Application filed May 31, 1930. Serial No. 458,211.

This invention relates to flyers for spinning machines and more particularly to one having completely replaceable parts.

Hitherto it has been proposed to use flyer blocks made of wood and brass.

These constructions require that the flyer wires be permanently associated therewith, which condition precludes the replacement of the wires as they break in service, due to the continued abrasive effect of the threads passing therethrough. In addition, mill nuts or like devices are often required to hold the members in place on the spindles. Where self-contained springs held in place by bushings have been used, the disadvantage of the mill nut has been obviated but the re-wiring of such devices is, in every instance, a custom job. Where devices of the type shown in the patent to H. E. Herr #1,614,552 have been used, considerable difficulty has been experienced with the maintenance and repair of these devices, due to the fact that special tools are required for the assembling steps, in order to remove broken wires and replace them with new ones, and in addition, the expansion anchoring sleeves frequently break and cannot be replaced; thus requiring scrapping of the entire unit.

It is an object of the present invention to provide a flyer for spinning purposes which is composed of a plurality of replaceable parts.

It is another object of this invention to provide an improved flyer of the type described which is freely movable and provided with replaceable parts throughout.

Yet another object of this invention is the provision of a novel flyer construction in which the flyer wires or arms serve as a locking means.

It is also an object of this invention to provide a flyer which can be readily assembled and disassembled and which cannot be placed in operation until the several parts are respectively placed in their correct operating positions.

These and other desirable objects of the present invention will be described in the accompanying specification and illustrated in the drawings, certain preferred embodi-

ments being shown by way of illustration only, for since the underlying principles may be applied to other specific devices, it is not intended to be limited to the ones here shown except as such limitations are clearly imposed by the appended claims.

In the drawings like numerals refer to similar parts throughout the several views, of which:

Fig. 1 is an elevation of the improved flyer of the present invention associated with a spindle and bobbin;

Fig. 2 is a top plan view of the construction shown in Fig. 1;

Fig. 3 is a vertical median section of the flyer block;

Fig. 4 is a front elevation of the top member of the flyer block.

Fig. 5 is a front elevation of the bottom flyer member;

Fig. 6 is an elevation of the locking spring member; and

Fig. 7 is a detail of the locking means for the flyer wires.

As shown in my application Serial No. 458,210 (Case A) filed May 31, 1930, flyer wires are subject to relatively frequent replacement due to the wearing out of the eyes by the abrasive action of the threads passing therethrough. In my above identified application, I have shown one form of a flyer device provided with replaceable parts and one in which the entire construction may be readily dismounted and reassembled in place on the machine at low cost and without requiring the shipment of the flyers to separate points for replacement of the flyer wires.

In the drawings there is shown the usual bobbin 1 mounted on spindle 2 with flyer block 3 and flyer wires 4 secured thereto. The flyer wires are provided with the usual eyelets 5, which as indicated in my application Ser. No. 458,210 filed May 31, 1930 (Case A) are provided with abrasion resistant metal. While abrasion resistant metal may be used it will of course be appreciated that mineral substances such as agate and the like may be made use of.

In the present invention, the flyer block 3

comprises an upper portion 6 having a central aperture 7 and internal female thread 8 and a shoulder portion 9 together with a bottom edge portion 10. The latter portion may be serrated as indicated in Fig. 4 for a purpose to be described more in detail herein-after. The lower portion 11 of member 3 is provided with a central aperture 12 registering with aperture 7 of member 6 and is also provided with an annular channel or flange 13 adapted to receive the member 10 of the upper portion of the flyer block. In addition, the member 11 is provided with a central portion 14 having a thread 15 formed thereon and adapted to engage a corresponding thread 8 in member 6. At its bottom or outer part, member 11 is provided with an internally extending shoulder portion 16 adapted to provide a support for the spring member 17. When members 6 and 11 are screwed together, the spring member 17 having been at first inserted within the central aperture of member 11, the spring will be held in position by the shoulders 9 and 16 of the cooperating members.

The flyer wires 4 are provided with the usual central curve portion 20 and lateral extending portions 21 adapted to engage apertures or slots 22 in section 13 of member 11. Section 20 of the flyer wires is bowed upwardly as indicated at 23 to permit a firm gripping thereof by serrated section 10 of member 6 when the flyer wire has been inserted in position and member 6 screwed up on member 11.

It will readily be seen that the improved flyer block of the present construction may be easily assembled and disassembled and worn parts replaced by other like parts without requiring the scrapping of an entire unit. In addition, one or more flyer wires may be made use of, the necessary tension being obtained by providing any desired angularity about the apertures 22 and the adjoining portions 24 of sections 13.

In operation, the spindle 2 will be directly engaged by the spring member 17 which may have any desired configuration or construction, a coil spring being shown here by way of example only, the said spindle engaging spring or coil being freely movable in its journal formed by the pill box construction of the abutting parts of the flyer block. While a serrated engaging portion 10 has been disclosed it will of course be appreciated that good results may be obtained by the use of a smooth surface but a serrated edge such as the one disclosed provides better locking for parts which are normally subjected to vibration stresses.

In accordance with the provisions of the patent statutes, I have described the principles of operation of my invention, together with the device which I now consider to represent a preferred embodiment thereof; but

I desire to have it understood that the device shown is only illustrative of the basic concept of the present invention, and that the said invention may be carried out by other means.

I claim:

1. A flyer including a body having a centrally apertured hub portion and an outer sheath adapted for threaded engagement with said hub, said sheath having a serrated bearing edge.

2. A flyer, including a bipartite body having a centrally apertured hub portion and a spindle engaging member in the hub, said hub being adapted for rotation about said spindle member, an outer sheath adapted for threaded engagement with said hub, and a flyer wire disposed between the hub and sheath and clamped therebetween.

3. A flyer, including a bipartite body having a centrally apertured hub portion and a spindle engaging member in the hub, said hub being adapted for rotation about said spindle member, an outer sheath adapted for threaded engagement with said hub, said sheath having a serrated clamping edge, and a flyer wire disposed between the hub and sheath and clamped therebetween.

4. A flyer, including a bipartite body having a centrally apertured hub portion and an expansible spindle engaging member in the hub, said hub being adapted for rotation about said spindle member, an outer sheath adapted for threaded engagement with said hub, and a flyer wire disposed between the hub and sheath and clamped therebetween.

5. A flyer, including a bipartite body having a centrally apertured hub portion and an expansible spindle engaging member in the hub, said hub being adapted for rotation about said spindle member, an outer sheath adapted for threaded engagement with said hub, said sheath having a serrated clamping edge, and a flyer wire disposed between the hub and sheath and clamped therebetween.

6. A flyer, including a bipartite body having a centrally apertured hub portion and a sheath adapted for threaded engagement with said hub, inner shoulders on the ends of said hub and sheath forming a cage in the hub, a freely movable expansible member disposed in the cage, flyer wire engaging means formed by the hub and sheath, and gripping devices formed on the said hub and sheath.

7. A flyer, including a bipartite body having a centrally apertured hub portion and a sheath adapted for threaded engagement with said hub, inner shoulders on the ends of said hub and sheath forming a cage in the hub, a freely movable expansible member disposed in the cage, a flange cooperating with the hub to form a channel, and wire

engaging means in said flange forming wire tensioning means with said hub.

8. A flyer, including a bipartite body having a centrally apertured hub portion and a sheath adapted for threaded engagement with said hub, inner shoulders on the ends of said hub and sheath forming a cage in the hub, an expandible spindle gripping member disposed in the cage and unconnected therewith, an outer skirted flange on said hub disposed around one end of said sheath, and wire tensioning means in said skirt cooperating with the body portion of the hub.

9. A flyer, including a bipartite body having a centrally apertured hub portion and a sheath adapted for threaded engagement with said hub, inner shoulders on the ends of said hub and sheath forming a cage in the hub, an expandible spindle gripping member disposed in the cage and unconnected therewith, an outer skirted flange on said hub disposed around one end of said sheath, wire tensioning means in said skirt cooperating with the body portion of the hub, and serrated means on said sheath for holding flyer wire in tensioned position.

10. A flyer, including a bipartite body having a centrally apertured hub portion and a sheath adapted for threaded engagement with said hub, inner shoulders on the ends of said hub and sheath forming a cage in the hub, an expandible spindle gripping member disposed in the cage and unconnected therewith, an outer skirted flange on said hub disposed around one end of said sheath, slots in said skirt cooperating with said hub to form flyer wire tensioning means, and means on said sheath for holding a tensioned flyer wire in operative position.

40 In testimony whereof I affix my signature.
MICHAEL J. McHALE.
